UNITED STATES PATENT OFFICE.

STANLEY W. WIDNEY, OF CHICAGO, ILLINOIS.

PIANO-PEDAL CONSTRUCTION.

1,176,118.

Specification of Letters Patent.

Patented Mar. 21, 1916.

Application filed September 26, 1914. Serial No. 863,614.

To all whom it may concern:

Be it known that I, STANLEY W. WIDNEY, a citizen of the United States, residing in the city of Chicago, county of Cook, and 5 State of Illinois, have invented certain new and useful Improvements in Piano-Pedal Constructions, of which the following is a specification.

My invention relates to improvements in 10 piano pedal constructions, and among its salient objects are, to provide a construction in which the shank of the pedal and the slot therefor are of such a character as effectually to prevent ingress of mice and other 15 vermin to the piano without the necessity of providing any special arrangement to exclude such animals; to provide a construction in which the pedal shank is so arranged as to be slightly resilient, and thus damage 20 to any of the parts of the structure is prevented in case the foot-piece of the pedal receives a heavy blow; to provide a construction of the class described in which the 25 foot-piece may be made of ornamental and graceful form free from obtrusive plates or projections to cover the shank slot; to provide a piano pedal shank of such a character as to admit the application of the prop to the same in an improved and efficient manner; to provide an improved construction 30 whereby the connection between the prop and the pedal shank admits of the use of a prop of exceptionally simple and efficient design, capable of being readily adjusted for 35 any desired throw; to provide a construction of the class described in which the various parts capable of relative mutual movement may be made free from squeak or other harsh noises during the operation of the 40 pedal; to provide a piano pedal construction which shall be cheap and economical to manufacture and capable of being easily operated and maintained; and, in general, to provide an improved piano pedal construction of the character referred to.

In the accompanying drawing—Figure 1 represents a fragmentary section of the lower corner of the case of a piano to which my invention is applied; Fig. 2 is a section 50 of Fig. 1 taken on the line 2—2; Fig. 3 is a section taken on the line 3—3 of Fig. 1; and Fig. 4 is an elevation of the prop.

Referring to the drawings, 10 represents the base-board of the piano case, the front 55 edge of which supports or is secured to the toe-rail 11 which forms a part of the front

of the piano case. Upon the base-board 10 I prefer to mount a bracket piece 12 which comprises a piece of sheet metal having a pair of upstanding ears 13 forming opposed 60 bearings for the pivot secured in the pedal shank 14. This pivot mounting, however, may be of any usual construction and forms no part of my present invention. The pedal shank 14 is an essentially novel feature of 65 my invention consisting of a relatively resilient strip of metal mounted on edge, as shown, and having its edges slightly rounded off, as shown, at 15 in Fig. 1 where it passes through the vertically extending slot 70 16 cut in the toe-rail 11. The slot 16 is bushed with felt 17, as shown in Fig. 2, in order to prevent the metal of the shank from striking or rubbing against the wood of the toe-rail and thus causing objectionable 75 noises or wear of the toe-rail. The outer end of the pedal shank 14 is secured in a slot formed in the lower corner of the foot-piece 18, either by a pair of rivets 19 or by any other suitable means; preferably the pedal is 80 inserted in the slot 16 when the lower end of the latter is open, before the toe-rail 11 and the base member 10 are placed together. Owing to the resilient character of the pedal shank 14, it will be observed that however 85 rigid and unyielding the pivot mounting 12 of the inner end of the shank, when the foot-piece receives a blow tending to bend the shank or strain the mounting, the shank will spring slightly and injury to the parts will 90 be avoided. Another advantage of the narrow shank is that it permits the use of a very narrow slot 16 and necessitates the provision of a pedal piece 18 having a rear end only of sufficient width to cover the narrow slot, and 95 consequently of a very neat and graceful appearance.

Where a rigid pedal shank is employed, invariably mechanical inaccuracies make it necessary to provide a considerable amount 100 of play in the slot. Obviously with this form of construction the shank cannot be supported by the sides of the slot, and if by any chance the pedal is struck sidewise a sufficiently severe blow the pedal mounting 105 is either broken or strained so that it becomes loose and wobbly. Since, however, with my construction I employ a comparatively thin thickness of felt for the sides of the slots and a very small amount of 110 clearance between the shank and the felt, the latter being admissible on account of the

resilient character of the mounting, when the resilient shank is pushed or knocked sidewise it flexes slightly and comes into bearing with the felt at the sides of the slot, preventing damage to the pivot mountings.

The flat shape of the pedal shank 14 and the manner in which it is mounted edgewise on its pivots, render it possible to use a novel and improved construction of prop 20, shown in Fig. 4. This prop 20 has the usual threaded upper end 21 which passes through the operating bar 22 and is engaged by a nut 23 resting upon the upper side of said bar. The lower end of the rod 20 is bent transversely at right angles, as shown at 24, and passes horizontally through one of the transverse apertures 25 punched or drilled through the shank 14, a plurality of these apertures being provided in order to admit of the adjustment of the prop 20 for different amounts of movement. In order to prevent the prop from becoming disengaged from the shank, I bend down the extremity of the transverse portion 24 at an angle, as shown at 26, this bend 26 being preferably bent parallel with the length of the prop and extending in a downward direction in order to facilitate the insertion of the prop in the shank. To prevent squeaks or noises caused by the relative movement of the prop and the shank when the pedal is operated, I prefer to bush the transverse hole 25, through which the prop passes, with a piece of felt 27 which extends out of the hole on either side a sufficient distance to be held in place between the projecting portions of the prop and the shank. I have found this construction of prop connection to be extremely cheap and economical in construction and exceptionally easy to apply to and adjust on the shank, since there are no screw connections or other loose parts at the point of its connection with the shank, it being itself self-retaining in position so long as it is held upright by the bar 22. When occa-

sion arises to remove the prop from the shank, the bar 22 is disconnected and the prop 20 bent at an angle and removed from the shank in an obvious manner.

My invention is not limited to the details of construction shown, except as specified in the appended claims.

I claim—

1. The combination with a horizontal pivot, and an operating bar designed for connection with a piano action, of a piano pedal-shank of relatively thin sheet metal mounted vertically edgewise on said horizontal pivot and having a transverse aperture therein, and a prop connecting said operating bar with said shank comprising a vertically extending rod bent at its lower end transversely to engage the transverse aperture of the shank, thence downwardly to substantial parallelism with the rod proper, to detachably retain the prop in operative position.

2. The combination with a piano-case provided with a base board, and with a toe rail having a single narrow slot for each pedal shank, of a bracket secured to the base board remote from the toe rail, a transversely apertured pedal shank of thin flat resilient metal pivoted to the bracket vertically as to its width and protruding at its forward end through the vertical slot in the toe rail, and a rigid pedal piece secured to the outer end of said shank, and a prop for connecting the operating bar of a piano action with said shank comprising a vertically extending rod bent at its lower end transversely to engage the transverse aperture of the shank, thence downwardly to substantial parallelism with the rod proper, to detachably retain the prop in operative position.

STANLEY W. WIDNEY.
